UNITED STATES PATENT OFFICE.

JOSEPH BARTL, OF CHICAGO, ILLINOIS.

ADJUSTABLE FASTENING DEVICE OR SASH-LOCK.

1,167,617.

Specification of Letters Patent. Patented Jan. 11, 1916.

Application filed October 28, 1914. Serial No. 868,926.

To all whom it may concern:

Be it known that I, JOSEPH BARTL, a citizen of the United States, and a resident of Chicago, in the county of Cook and State of Illinois, have invented certain new and useful Improvements in Adjustable Fastening Devices or Sash-Locks; and I do hereby declare that the following is a full, clear, and exact description thereof, reference being had to the accompanying drawings, and to the letters of reference marked thereon, which form a part of this specification.

This invention relates to adjustable fastening devices or sash locks.

It relates particularly to fastening devices or sash locks for fastening inner and outer or upper and lower sashes of windows together in different adjusted positions.

The principal object of the invention is to provide a simple, economical, and efficient fastening mechanism, adapted to securely fasten or lock a sash or similar device in partially opened or in closed position, as desired.

A further object is to provide a fastening device adapted to secure the inner and outer or upper and lower sashes of a window together, with the window closed, and to enable the sashes to be fastened or locked together on the inside, with the upper sash lowered or with either or both sashes partially opened or moved from closed position, in such a manner that the releasing of the fastening means, and the disconnecting of the sashes from the outside while the window is open or partially open, will be prevented.

Other and further objects of the invention will appear from an examination of the following description and from an inspection of the drawings which are made a part hereof.

The invention consists in the features, combinations, and details of construction herein described and claimed.

In the accompanying drawings, Figure 1 is a view in elevation of a window-fastening device or fixture, constructed in accordance with my invention and improvements, and showing the same in operative position upon the sashes of a window, the fastening device being shown with the parts in position for fastening closed sashes together in full lines, and with the hooked arm or guard in raised position in broken lines; Fig. 2, a view in vertical section, taken on line 2 of

Fig. 1, showing the pivoted securing arm, guard or hook in raised position so as to permit one or both of the sashes to be moved to open or partially opened position upon turning the horizontally movable, pivoted catch on the inner sash member to releasing position or out of engagement with the fastening member on the outer or upper sash; Fig. 3, a plan view of the window-fastening device shown in Fig. 1, with the pivoted guard or hook shown in horizontal section, as it would appear when in raised position, and showing the horizontally movable, pivoted member in locking position in full lines and in releasing position in broken lines; Fig. 4, a view in central vertical section of the device shown in Figs. 1, 2 and 3, with the upper sash slightly lowered with respect to the lower or inner sash, and with the parts of the fastening device in position to prevent the further lowering or opening of the sash from the outside; Fig. 5, a similar view in vertical section, showing the parts of the fastening device in position to fasten the sashes together with the upper sash lowered to a greater extent, or with the sashes further opened than they are shown in Fig. 4 and adapted to permit the sashes to be raised or lowered together and to prevent them from being further opened from the outside; Fig. 6, a detail view in elevation of the window-fastening member for the outer or upper sash, showing the pivoted hooked arm or guard in raised position; Fig. 7, a detail view in vertical section, taken on line 7 of Fig. 3 looking in the direction of the arrow, and showing the spring for yieldingly pressing the hooked arm or guard inward into position to be securely held in upright position; Fig. 8, a detail plan view of the base or fixed bottom member of the part of the fastening device which is secured to the inner or lower sash and which is provided with a loop or socket into which the hooked arm or guard extends when the sashes are secured in partially opened position or with the upper sash partially lowered with respect to the lower sash; Fig. 9, a view in elevation of the base member shown in Fig. 8, with the pivoted catch or locking lever member thereon as it would appear when seen from the outside; Fig. 10, a view in elevation of a window, comprising an upper and lower sash provided with a sash-fastening device or mechanism constructed in accordance with my

invention, and showing the upper sash in partially opened position and fastened or attached to and movable with the lower or inner sash, or in a position corresponding with the position of the parts as shown in Fig. 5; and Fig. 11, a view in elevation of a modified form of securing hook or hooked guard arm having a relatively long hook and a spring attached to the stem or pivoted end of the arm and adapted to engage the supporting bracket in which such guard arm is pivotally supported.

In constructing a fastening device, locking guard, or sash-lock in accordance with my invention and improvements, I provide a locking or pivoted catch member or latch 12 adapted to be mounted on a movable member to be locked, such as an inner or lower sash *a*, and a pivoted hook member or guard 20 *t* which is adapted to be mounted on an outer or upper sash *b*. The sashes *a* and *b* shown in the drawings are usually mounted in a window frame comprising side frame members *c*, a top frame member *d*, a bottom frame member *e*, and window stops *f* and *f'*, all of which may be of any desired, ordinary or well known form. The bottom or inner sash shown in the drawings comprises the usual side members *g*, bottom member *h*, and top sash member *i*, slidably mounted between the window stops *f* in the ordinary manner, and the upper or outer sash comprises side members *k*, a top member *l*, and a bottom member *m* forming a supporting 35 frame for a window pane *n*, said sash being also slidably mounted between inner and outer window stops *f* in the ordinary manner.

A latch or locking and releasing catch is 40 mounted on the inner or lower sash and comprises in its construction a metallic base and loop or socket-forming member *o*, which is mounted upon and securely attached to or anchored in the upper or horizontal sash member *m* of the lower or inner sash, by means or screws or rivets *p* or other suitable securing means. (See Figs. 2, 3, 8 and 9.) This base member is provided with an integral loop portion *q* on the side adjacent 45 to the upper or outer sash, forming a socket having a recess or vertical slot *r* adapted to admit the depending upright hook portion *s* of a hooked arm or guard member *t*, which is mounted on the adjacent outer or upper sash. Said arm or guard member is pivotally secured to the outer or upper sash by 50 means of a supporting bracket *u* having a base portion *v* provided with apertures *w* adapted to admit securing screws or rivets 55 or other suitable securing means for anchoring or rigidly securing said supporting bracket to the bottom member *m* of the outer or upper sash and on the inside of the window pane of said sash. This 60 supporting bracket or member *u* is pro-

vided with a vertical or upwardly and laterally opening recess or slot *y*, into which the lower or pivoted end of the hooked arm or guard member *t* extends, (see Figs. 2, 3, 6 and 7), and said pivoted hooked arm or 70 guard member *t* is provided with an elongated aperture 2 therethrough, through which extends a horizontal pivot 3, one end 4 of which is rigidly secured in a suitable perforation in the bracket member *u*, preferably by being riveted to said bracket member, and the other end of which is provided with a head 5 or similar suitable arm-engaging means adapted to securely hold the arm *t* upon the pivot or pin 3. The 80 bracket member *u* has securing shoulder portions 6, 6, which are adapted to engage the arm or guard member *t* when the latter is in upright or raised position between said shoulder portions (see Figs. 2 and 3), and a 85 spring 7 is mounted upon, and by preference inside of the bracket member *u* and in position to project at an incline into the slot *y* of said bracket member *u*. This spring is securely held in operative position by means 90 of a shoulder portion 8 of the pivot pin or rivet 3, the upper portion 9 of said spring being in yielding engagement with an outwardly facing part of the pivoted arm or guard member *t*. (See Figs. 2 and 3.) The 95 spring is thus adapted to yieldingly press said guard or hooked arm inwardly into the recessed portion 10 and between and removably in engagement with the shoulders 6 of the bracket member *u*, in which recessed 100 portion said arm or guard is yieldingly held in upright position. The hooked arm or guard member *t*, thus held in upright position, cannot be lowered or turned downward or to horizontal position except by first 105 pressing said guard member outward out of engagement with the shoulders 6 and then turning the same downward.

The bracket member *u*, which forms a support for the hooked arm or guard member *t*, is provided with a rigid securing hook or latch-engaging shoulder portion 11 in the upper portion of said bracket member, which projects inward or toward the inner or adjacent sash. Said fixed shoulder or hooked 115 portion 11 is above the level of the loop portion *q* of the member *o* on the inner or lower sash when the sashes are in normal or closed position and in position to project over and in securing or locking engagement with a 120 pivoted latch member or catch 12 on the inner or lower sash. The latch member or catch 12 is pivotally mounted upon the base member *o* to which it is secured by means of a suitable vertical pivot 14, said pivot being 125 secured to the base member *o* by means of a nut or riveted end portion 15, or other suitable securing means. The latch or securing member 12 has an operating lever or handle portion 13, and is provided with a circular 130

or segmental, peripheral rim portion 16 which extends upward and in the direction of the projecting end portion 13 of the lever at an incline. (See Figs. 1 and 2.) The 5 curved and inclined edge or rim portion is thus adapted to extend into interlocking engagement with the slotted or recessed under side portion 17 of the fixed hook 11, already described. A boss or depending sleeve portion 18 on the latch or sash-lock member 12 extends into a suitable recess 19 in the part *o* and, with the vertical pivot pin 14, serves to securely hold the latch or sash-lock member 12 in position to enable the latter to be readily turned in a horizontal plane into and out 10 of locking engagement with the fixed hooked portion 11 of the bracket member *u*, and into and out of locking engagement with the pivoted hooked arm or guard member *t* when the latter is in upright or operative position 15 with the upper sash partially lowered with respect to the lower sash, or with the sashes or either of them in partly opened position. (See Figs. 2, 4 and 5.)

25 The loop portion *q* is provided with an upwardly opening notch or recess *q'* having side shoulder portions *z* which engage the horizontal or bow portion *z'* when the hooked arm or guard member *t* is in locked position 30 between the loop *q* or base *o* and the pivoted locking member 12. (See Figs. 5, 8 and 9.) The outwardly or rearwardly facing opening or slot *q'* may be as much narrower than the oval or elliptical slot or socket portion *r* 35 as desired and may be of any desired length vertically so as to bisect the loop *q* to any desired extent, and the sash member *i* has a recess 20 directly beneath the slot or opening *r* in the inclined outer side face of said 40 sash member, said recess being tapered in the direction of its lower extremity so as to leave the outer bottom edge of the sash member *i* unbroken and straight or whole, and permit the vertical hook portion *s* to extend 45 through the slot *r* in the loop *q* and into or through the recess 20. (See Figs. 2, 5 and 9.)

In Fig. 11, a modified form of hooked guard arm and spring is shown, in which the spring 7^a is shown mounted on the pivoted arm member *t* and in yielding engagement with the bracket member *u*. The arm *s* of the hook member being of such length that when it is in raised or upright position 50 its lower end will extend down to a point so near to the top of the slot *r* and loop *q*, when the sashes are in closed position, that the first movement of the upper sash downward with respect to the lower sash or of 55 the lower sash upward with respect to the upper or outer sash will cause the lower end of the hooked arm portion *s* to at once extend into the socket *r* or loop *q* and lock the sashes together in such a manner as to 60 permit them to be moved to partially opened

position, but positively limit the extent to which they can be opened, and prevent the removal of the hooked arm portion *s* from locking engagement with the loop *q* excepting only when the sashes are in closed position. 70

In operation, the sashes may be locked in closed position, as shown in Figs. 1 and 2, by turning the pivoted latch or locking member 12 into position to extend into locking engagement with the fixed hook portion 11 of the bracket member *u*, so that the curved rim or flange portion 16 is in the notch or recess 17, as shown in said Figs. 1 and 2. The hooked arm member or guard 80 *t* is adapted to be placed in normal or horizontal position, as shown in full lines in Fig. 1, so as to permit the sashes to be opened upon turning the pivoted catch or locking member 12 to releasing position or 85 out of engagement with the part 11 of the bracket member *u*. The locking member 12 is shown in locking position in full lines in Fig. 3, and in releasing position in broken lines in the same figure. The hooked arm *t* 90 may be moved to and allowed to remain in raised upright position, as shown in broken lines in Fig. 1, with the catch 12 either in locking or releasing position as desired. By having the pivoted catch or locking member 95 12 turned to releasing position with the hooked arm or guard *t* in upright position, it will be readily seen that the lower sash may be raised or the upper sash lowered to such relative positions that the hook or 100 arm *s* is in position to extend through the loop *q*, with the upper extremity or bow portion *z'* of the hook member in engagement with the loop *q* and in position to be locked in engagement with said loop by 105 turning the pivoted catch or sash lock member 12 into locking position, or into position to extend over and in locking engagement with said upper extremity or bow portion of the hook member or guard *t*. (See Figs. 5 and 10.) The sashes are thus securely locked in fixed relation, and in position to permit 110 the top sash to be partly open at the top or the bottom sash partly open at the bottom or both sashes in position to leave an opening at 115 top and bottom, for the purposes of ventilation, etc., but with both sashes securely locked together in such a manner that neither sash can be opened to any greater extent than that permitted by the hooked arm member *t* and the locking members comprising the base or socket member *o* with its loop *q* and socket or opening *r*, the pivoted latch or sash lock member 12, and the bracket *u* with which the hooked arm or 120 guard member *t* is pivotally connected. The releasing or unlocking of the sash fastening or locking mechanism from the outside is thus prevented, not only when the sashes are in closed position but also when either 125 either

130

or both sashes are in partially open position, and the extent to which the sashes or either of them can be opened is positively limited, and the sashes are securely locked together with either or both sashes in partially open position. The top sash may be lowered from the inside with facility by first raising the lower sash and locking the sashes together and pulling down upon the lower sash, thus bringing both sashes down to the position shown in Fig. 10. The rattling of the sashes is prevented not only when they are closed but when they are connected together in partially opened position as described.

A shoulder portion s' is provided upon the lower extremity of the arm s of the hooked arm member t , and the bottom end portion 21 of the arm s is offset with respect to or of smaller cross-sectional area than the shoulder portion, so that the part 21 is adapted to extend through the opening 17' in the pivoted catch or sash lock member 12, when the latter is in locking position, as shown in Fig. 4. The further movement of the part s with respect to the catch 12 and loop q is thus prevented by the shoulder or bottom extremity of the hook portion s . The mechanism is thus adapted to be locked in the position shown in Fig. 4, in which position the sashes are securely locked in a different partially open position from that in which they are shown in Figs. 5 and 10. With the parts in the position shown in Fig. 35 4, the locking member or pivoted catch 12 is prevented from being turned to releasing position until the outer sash is raised or both sashes are closed, so as to bring the bottom end of the part 21 or hooked arm portion s 40 cut of engagement with the opening 17' in the pivoted sash locking member 12. The pivoted locking member 12 can then be turned to releasing position, and from releasing position back to locking position or 45 to position to permit the part 21 to pass through the opening 17' with the sashes in the partially opened position in which they are shown in Fig. 4.

I claim:

50 1. In a fastening device of the class described, the combination of a socket member, means for securing the socket member to a window sash, a hooked guard arm pivotally connected with a sash located adjacent to the sash to which said socket member is secured, said guard arm comprising a main body portion and a hook portion which extend in substantially parallel relation, the hook portion of said guard arm member 55 being movable into and out of interlocking engagement with said socket member, said socket member being slidable longitudinally of said hook portion with said interlocking parts in interlocking engagement and with 60 said hook portion extending through the

socket member, and a pivoted locking member operatively connected with the socket member and adapted to be moved into and out of locking engagement with the guard arm at the intersection of the hook portion 70 and main body portion of said guard arm member.

2. In a fastening device of the class described, the combination of a socket member, means for securing the socket member to a window sash, a hooked guard arm pivotally connected with a sash located adjacent to the sash to which the socket member is secured, said hooked guard arm comprising a main body portion and a hook portion 80 extending in substantially parallel relation, the hook portion of said guard member being movable into and out of interlocking engagement with the socket member, and said socket member being adapted to slide upon said hook portion with said interlocking parts in interlocking engagement, and means for securing the pivoted guard arm in upright position.

3. In a fastening device of the class described, the combination of a socket member, means for securing the socket member to a window sash, a hooked guard arm pivotally connected with a sash located adjacent to the sash to which the socket member is secured, said hooked guard arm comprising a main body portion and a hook portion extending in substantially parallel relation, the hook portion of said guard member being movable into and out of interlocking engagement with the socket member, and said socket member being adapted to slide upon said hook portion with said interlocking parts in interlocking engagement, means for securing the pivoted guard arm in upright position, and a locking member operatively connected with the socket member and movable into and out of locking engagement with the hooked guard arm.

4. In a fastening device of the class described, the combination of a socket member, means for securing the socket member to a window sash, a hooked guard arm pivotally connected with a sash located adjacent to the sash to which the socket member is secured, said hooked guard arm comprising a main body portion and a hook portion extending in substantially parallel relation, the hook portion of said guard member being movable into and out of interlocking engagement with the socket member, and said socket member being adapted to slide upon said hook portion with said interlocking parts in interlocking engagement, a detent adapted to engage the pivoted guard arm, 110 for holding the latter in upright position, and a spring in operative engagement with said guard arm, for yieldingly holding the latter in position to engage the socket member and detent.

5. In a fastening device of the class described, the combination of a socket member, means for securing the socket member to a window sash, a hooked guard arm pivotally connected with a sash located adjacent to the sash to which the socket member is secured, said hooked guard arm comprising a main body portion and a hook portion extending in substantially parallel relation, 10 the hook portion of said guard member being movable into and out of interlocking engagement with the socket member, and said socket member being adapted to slide upon said hook portion with said interlocking parts in interlocking engagement, a detent 15 adapted to engage the pivoted guard arm.

for holding the latter in upright position, a spring in operative engagement with said guard arm, for yieldingly holding the latter in position to engage the socket member and detent, and a locking member operatively connected with the socket member and movable into and out of locking engagement with the hooked guard arm. 20

In testimony that I claim the foregoing 25 as my invention I affix my signature, in the presence of two witnesses, this 19th day of October, A. D. 1914.

JOSEPH BARTL.
